WIRELESS RECEIVING SYSTEM

Aristote Mavrogenis, Milwaukee, Wis.

Original application April 15, 1929, Serial No. 355,153. Divided and this application September 5, 1933, Serial No. 688,233

34 Claims. (Cl. 250—27)

This invention relates to wireless receiving systems, and is particularly directed to a system including wireless receiving apparatus and a translating device for translating electrical impulses into mechanical motion, for example, sound waves.

An object of the invention is to provide means in a radio receiving apparatus having amplifying means, detecting means, and a translating device having field producing means, which means enables different parts of the system to be supplied from an alternating or variable current source, such, for example, as the city electric lighting and power circuit, without any objectionable disturbance due to the variations of potential or current from this source.

Further objects of this invention are to provide a novel system having a source of energy supply, a translating device provided with a field producing means or unit, and electron discharge devices so associated with the field producing means or unit of the translating device that the source supplies the output circuit or circuits of one or a plurality of electron discharge devices and also the field producing means or unit of the translating device.

This invention is an improvement over the invention disclosed in my application S. N. 669,490, filed October 19, 1923, for a Wireless receiving system, in which a translating device is employed having field producing means supplied from an alternating current source, and in which the field producing means is energized from the alternating current source and may aid in smoothing out pulsations in the rectified current supplied to an element of the vacuum tubes employed in the system, all of the tubes being energized from said alternating current source. The present case in fact contains many of the disclosures also appearing in said earlier application S. N. 669,490.

It is the usual practice where translating devices are employed, such, for example, as dynamic loud speakers, to utilize a storage battery for supplying the field current for the loud speaker and to utilize a separate B battery or B eliminator for supplying the output circuits of the vacuum tubes. This arrangement necessitates an elaborate equipment which is expensive and which has a large number of elements or parts.

This invention is designed to overcome the defects noted above, and further objects are to provide a novel arrangement of connections between the translating device, the source of alternating current, and the output or anode circuits or electrodes of a plurality of electron discharge de-

vices, whereby the field producing means or unit is utilized to aid in smoothing out any pulsations of current supplied from the A—C source to the output circuits or electrodes of the electron discharge devices.

Further objects are to provide a wireless receiving apparatus which is so made that the rectifying apparatus and the associated electrical circuits may be very much simplified due to the use of the field producing means or unit of the translating device, in which a compact and simple arrangement is provided and in which the system may be made at a relatively small manufacturing cost.

Further objects are to provide a radio receiving system having a plurality of cooperating electron discharge devices adapted to be supplied from an alternating or variable current source or supply means, in which at least one of the electron discharge devices has an indirectly heated cathode connected to an anode through at least a part of an electrical circuit including rectifying means or current converting means with or without smoothing means, and in which a translating device is employed whose field producing means is supplied from the alternating or variable current source or supply means, and in which the field producing means may aid in smoothing out pulsations in at least a part of the rectified current supplied one or more of the electron discharge devices.

Another object is to provide a radio receiving system, in which the field producing means or field winding of the translating device is provided with a tap which is adapted to be connected to any point of the system or to the electrodes of the vacuum tubes thereof, such as grids or screen grids, for maintaining the same at a suitable potential from a power source.

A further object is to provide a radio receiver, in which a plurality of filter reactances or inductances is employed, which devices are connected at various points to the anodes or anode circuits of the thermionic devices, and in which one of the said reactances or inductances forms the field producing means of the translating device.

Another object is to provide a radio receiver, in which the field producing means or winding of the translating device is employed to secure diverse operating potentials for the vacuum tube electrodes, such as the anodes or anode circuits.

A further object is to provide a radio receiving system, in which a plurality of current con-

110

verting or rectifying circuits are employed which have a plurality of positive output terminals.

Another object is to provide a radio receiver, in which means are embodied to protect the 5 vacuum tubes and/or the translating device from excessive operating voltages.

A further object of the invention is to provide a radio receiver, wherein means are provided across the field producing means of the translating device for securing suitable and/or different operating potentials for the thermionic devices thereof, from a power source.

A further object of this invention is to provide a system, in which the field producing means or 15 unit of the translating device cooperates with other parts of the system to provide a constant voltage for some point in the system.

Further objects of the invention will appear hereinafter as the description proceeds.

20 This case is a division of my application S. N. 355,153, filed April 15, 1929.

Embodiments of the invention are shown in the accompanying drawings, in which:

25 Figure 1 is a diagrammatic view showing one form of the invention, in which the output circuits of all the tubes are supplied through a field unit of the translating device.

30 Figure 2 is a diagrammatic view, in which a plurality of the tubes are supplied through the translating device, the two rectifiers being shown in Figure 2 as separate units.

35 Figure 3 is a diagrammatic view showing a further form of the invention and a different manner of associating the field producing means or unit of the translating device.

Figure 4 is a still further form of the invention.

Figure 5 is a sectional view, partly diagrammatic, showing one of the many forms that the translating device may take.

40 Referring to Figure 1 showing the first form of the invention, it will be seen that a plurality of electron discharge devices 1, 2, 3 and 4 have been shown as interconnected or associated with each other in a wireless receiving system. If desired, 45 the first tube 1 may be a radio frequency amplifier, the second tube 2 may be a detector, the third tube 3 may be an audio frequency amplifier, and the fourth tube 4 may be a power amplifier. Each of the tubes is provided with a filament 5, 50 and the filaments are connected in parallel and supplied with alternating current from the secondary 6 of a transformer. The center point of the secondary is connected to the bus-bar 7 and one side of each of the grid circuits is connected 55 to this bus-bar. Any suitable means for tuning the desired circuits of the system may be employed, and if desired, a resistance 8 may be placed in the grid circuit of the first tube to suppress oscillations, and a volume control 9 may 60 be placed in the grid circuit of the audio frequency amplifier 3.

The supply transformer is provided with a primary 10 connected to the supply main and in the form shown in Figure 1 this transformer is provided with a plurality of secondaries. One of the secondaries 11 is connected to the filament or cathode 12 of the rectifier 13 and serves to heat the filament. Another secondary 14 has its opposite ends connected to the plates or anodes 15 of the rectifier. The neutral point or center point of the secondary 14 is connected to the negative bus-bar or conductor 16 of the electrical filter circuits, and bus-bar 16 is connected also to the center point or neutral point of the secondary 6. 75 The other side of the filter system or supply

system is connected to the center point of the secondary 11. This circuit leads through a choke coil 17, through the winding of a field unit 18 of a translating device, such as a dynamic loud speaker, and to the positive end of a resistance 19. The negative end of the resistance is connected to the conductor or bus-bar 16.

80 It is apparent from the description thus far given that current flows from one or the other of the anodes 15 of the rectifier, to the cathode 12 from a neutral point of the secondary 11, through the choke coil 17, through the field producing means or unit 18 of the loud speaker, through the resistance 19, and back to the neutral point of the secondary 14.

85 These electrical circuits may constitute filter circuits and may be supplied with appropriate filter condensers 20, 21 and 22, the condensers 20 and 21 being located on opposite sides of the choke coil 17 and the condensers 21 and 22 being located 90 on opposite sides of the field unit 18.

95 The plate circuits of the several tubes are supplied from the filtered current, which passes through the filter circuit, such filter circuit co-operating with or including the field producing means or unit of the loud speaker or translating device 26.

100 It is to be noted at this point that, by utilizing the field producing means or unit of the loud speaker or other translating device, the size of 105 the parts of the filter circuit may be greatly reduced, with consequent reduction of the cost of manufacture and with an increase in compactness. The field producing means or unit of the translating device supplies a large impedance 110 which cooperates directly with the other parts of the electrical circuits in smoothing out pulsations in the rectified current.

115 Any suitable connection may be provided from the plates or anodes of the several tubes to the supply system or filter system. For example, the plates of the tubes 1 and 3 may be connected to a selected point of the resistance 19 by means of the conductor 23, the plate of the detector tube may be connected to a different selected point by 120 means of the conductor 24, and the plate of the power amplifier 4 may be connected through a suitable device coupled to the loud speaker and with a selected point, for example, the positive terminal of the resistance 19, as shown in Figure 1. 125 The plate circuit of the power amplifier is connected to the moving coil or receiving coil of the translating device in any suitable manner, as by means of a transformer housed in the casing 25 carried by the translating device 26, in accordance with the usual practice, although it is to be distinctly understood that any appropriate method 130 may be followed for connecting the receiving coil or armature member of the translating device to the desired output circuit.

135 It is to be noted that, with reference to Figure 1 or Figure 2, hereinafter described, the resistance 19 may be either a continuous resistance member or a plurality of distinct elements arranged either in series or in parallel and supplied from the alternating supply source through the current converting or rectifying device, as shown in Figure 3, if so desired.

140 By-pass condensers 27 and 28 are provided for by-passing the different portions of the resistance 19 as shown in Figure 1, so that the variable portion of the different cathode-plate currents do not have to traverse the resistance 19. The condenser 29 by-passes the field unit 18. This last mentioned condenser 29 may be omitted if desired. 145 150

This improves the clarity of reception and also the volume.

It may be found desirable to provide one or more of the electron discharge devices with equi-
5 potential or indirectly heated cathodes. For in-
stance, the detector tube 2 has been shown in Fig-
ure 1 as provided with an equipotential or indi-
rectly heated cathode 30 heated by the filament
10 and connected to the conductor 7 and, conse-
quently, to the negative side of the filter system
or supply system. Referring to Figure 1, it will
be seen that, although a single current convert-
ing or rectifying device is embodied in the system
15 for supplying a unilateral current at a mean po-
tential of a certain value for a given setting, the
anodes of the electron discharge devices are
adapted to be supplied with different suitable po-
tentials and need not all be supplied at the same
20 potential. Very clearly, if desired, several elec-
tron discharge devices may be supplied at the
same potential.

Figure 2 shows a further form of the invention employing the same principles as those illus-
trated in Figure 1, but showing a slightly differ-
25 ent arrangement. In the form shown in Figure
2, a resistance 31 is bridged across the secondary
6 or filament secondary of the transformer and
is connected to the neutral or negative bus-bar
7 of the system and also to the negative bus-bar
30 16 of the filter circuits or electrical supply cir-
cuits. The secondary 14 is connected to the
plates 32 and 33 of the rectifiers 34 and 35. The
center point of the secondary 14 is connected to
the bus-bar 16. The filaments or heaters 36
35 and 37 of the rectifiers may be connected in par-
allel and supplied from the secondary 11. The
center point or neutral point of the secondary
11 is connected to the filter system in the same
manner as that previously described. The tubes
40 1, 2 and 3 are supplied from the filter system
by connecting their plates with appropriate
points of the resistance 19.

It is to be noted that in the form shown in
Figure 2 all of the plate current for the tubes
45 1, 2 and 3 passes through the field unit 18 of the
translating device 26. However, the plate of the
power amplifier 4 is connected to a point in the
filter system, indicated by the reference char-
acter 38, in advance of the field unit 18 of the
50 translating device. In other words, the plate
current of the power amplifier in this form of
the invention does not pass through the field pro-
ducing means or unit of the translating device.
The anode or anode circuit of any of the tubes
55 1, 2 and 3 is, therefore, maintained at a potential
different from that applied to the anode, or to
the anode circuit, of tube 4 by means of this
field unit or winding, inasmuch as a voltage
drop is produced in this field winding due to the
flow of current which is supplied therethrough to
the anode or anode circuit of any of these tubes
1, 2 and 3.

It is to be distinctly understood that other
arrangements could be made and the current
supplying any given tube or any group of tubes
could be passed through the field producing
means or unit of the translating device.

In the form shown in Figure 3 a regenerative
detector 39 is employed and its output circuit is
coupled or connected to the audio frequency am-
plifier 40, which is, in turn, coupled or connected
to the audio frequency amplifier or power tube
41. These tubes have their filaments or cathodes
70 connected in parallel and supplied with rectified
current, the terminals of the filament circuits

being connected across the element 42 of a re-
sistance. Of course, the cathode of any of said
tubes, such as that of tube 39, for instance, may
be an indirectly heated cathode, as shown in
Fig. 1, Fig. 2 and Fig. 4, and may be also ener-
gized in similar manner to the cathodes of the
tubes of said Fig. 1, Fig. 2 and Fig. 4, if so de-
sired. The element 42 of the resistance is con-
nected by means of a tap switch 43 to any de-
sired point of the resistance element 44. The 85
resistance element 44, similarly, may be connect-
ed by means of a tap switch 45 to any desired
point of the resistance element 46. The resistance
made up of the elements 42, 44 and 46 is con-
nected to the output terminals 47 and 48 of a 90
filter system hereinafter described.

The terminal 47 may be positive and the ter-
minal 48 negative as indicated.

The filter system or electrical supply circuits
may, in this case, comprise a rectifier provided
with an anode 49 and a cathode or filament 50.
The anode 49 or plate of the rectifier is con-
nected to one end of the supply secondary 51,
the primary 52 of the supply transformer being
connected to the mains, as shown also in Figures 100
1 and 2. The other side of the secondary 51 is
connected to the negative terminal 48 as pre-
viously mentioned.

The cathode or element 50 of the rectifier is
connected through a suitable choke coil 53 with 105
the anode or plate 54 of a current limiting device.
The current limiting device is provided with an
equipotential cathode 55 heated by a filament 56.
The cathode 55 of the current limiting device is
connected to the positive terminal 47. The rec-
tifier and current limiting device may take the
110 form of that disclosed in my Patent No. 1,671,598
for rectifiers issued May 29, 1928, the current
limiting device acting to hold the current at a
fixed predetermined value, as well as acting as
115 a resistance or impedance device, thereby aiding
in smoothing out pulsations in the rectified cur-
rent. The choke coil 53 and condenser 57 serve
to at least partly suppress the pulsations in the
rectified current prior to their arrival at the 120
current limiting device.

Inasmuch as the current limiting device gives
a substantially constant current for any given
setting of the rheostat of its filament, it is appar-
ent that, when the number of tubes is varied,
some by-passing means is preferably provided for
125 by-passing a portion of the current from the cur-
rent limiting device. For example a by-pass re-
sistance 58 may be bridged across the terminals
47 and 48, any suitable value of the resistance
being selected by means of the tap switch 59. 130

It is apparent from the description given above
that through one or more of the switches 43, 45
and 59 a shunt path or shunt paths, a short circuit
or short circuits, may be established around a
portion or portions of the composite resistance
42 to 46, or through the resistance 58 or a por-
tion thereof respectively, whereby the anode po-
tential or potentials of the tube or tubes remain-
ing in operation is or are prevented from being
135 unduly increased, when either the field producing
means of the translating device 26 or one or more
of the tubes of the system is or are not simul-
taneously supplied from same power supply source
or means.

It is apparent from the description given above
145 that current flows through the composite resist-
ance formed of the elements 46, 44 and 42. The
plate circuits for the tubes may be connected at
the desired point and the filament circuit of the 150

tubes or electron discharge devices also may be connected at the desired points and may thus be supplied by the rectified current. Further, the field producing means or unit 18 of the translating device 26 may be connected to suitable points of the composite resistance and may thus be energized. In fact, the said composite resistance and resistance 44' are mounted in shunt to said field winding or unit, which is shown in detail in Figure 5 and designated by reference character 77.

A resistance 44' is bridged between the output circuits and the negative terminals of the electron discharge devices, and is used to by-pass current from the output circuits of the devices, as this current varies, whereas the current limiting device maintains a steady current.

It is to be noted in connection with Figure 3 that the field unit of the loud speaker is in parallel to the composite resistance and, consequently, is in effect in parallel to the plate circuits of the electron discharge devices.

Figure 4 shows a still further form of the invention. The arrangement of electron discharge devices is substantially similar to that described in connection with Figures 1 and 2. The filaments, however, are arranged in two groups and are supplied by two distinct secondaries. The center point or neutral point of each of these secondaries 61 and 61' is connected to the corresponding neutral bus-bar 62 and 62', respectively. Further, the secondary 60 is employed to supply the filament 63 of the rectifiers 64 and 65. The plate 66 of the rectifier 64 is connected to the negative end of the resistance 67. The other end of the resistance 67 is connected through a choke coil 68 to one end of the secondary 69 for the rectifiers. The other end of the secondary 69 is similarly connected to one end of a choke coil 70, the choke coil 70 being connected to the positive terminal of the resistance 71, the negative terminal of such resistance being connected to the plate of the rectifier 65.

The center point of the secondary 69 is connected to the center point of secondary 60. Suitable filter condensers are provided as indicated at 72 and 73, and 72' and 73', and may be associated with the choke coils 68 and 70, as shown in Figure 4. The terminals of the field unit 18 of the translating device 26 may be connected to the resistance 67, as shown in Figure 4, also suitable by-pass condensers 74, 75 and 76 may be provided as shown in Figure 4 and may operate in substantially the manner previously described in connection with Figure 1. Further the plates of the different tubes may be connected to selected points of the resistance 67, or of the resistance 71, as shown in Figure 4. The last tube 4 may, if desired, be a power amplifier.

It is to be noted in connection with the last described form of the invention that the field producing means or unit 18 of the translating device is in effect parallel to the plate circuits of the electron discharge devices. Similarly, the said field unit or winding is in effect in parallel with resistance 67. It will be seen, therefore, that a novel circuit arrangement is provided by this invention in a radio receiver, which reduces any possible undesirable inter-part or interstage coupling, improves the operating characteristics of the receiver, and renders the operating voltage or current supply for the various parts of the apparatus more flexible, and thereby secures a smoother and more stable operation thereof.

Any suitable form of translating device may be

employed. For instance, it is apparent that the receiving coil of the translating device may be a movable coil connected to the diaphragm of a horn or to a cone or may be connected to any other part which is to be mechanically moved. Obviously link mechanism could be interposed between the movable receiving coil and the diaphragm or cone, if so desired. Further, it is obvious that the receiving coil could be a stationary coil, as in certain types of loud speakers. One form, however, has been chosen for illustration and is shown in Figure 5. The field producing means or unit 18 is energized by a field coil 77 which may be wound about a circular core 78. The outer shell furnishes the return magnetic circuit. A disk 79 is connected to the outer end of the outer shell and is provided with a circular aperture through which the reduced portion 80 of the circular core passes. Between the disk 79 and the circular core, the receiving coil or armature member 81 of the translating device is positioned. This receiving coil is, in the form shown, a moving coil and is connected to the diaphragm 82 of a horn; in fact, the moving coil is carried by the diaphragm of the horn or cone in the form shown in Figure 5. The receiving coil 81 may be connected to the output circuit of the last tube by means of a small transformer enclosed in the casing 25 and having a primary 83 and a secondary 84 connected to the receiving coil as shown in Figure 5. It is, obvious, however, that the receiving coil or armature member could be connected to the output circuit of the last tube or power amplifier in any desired manner.

It is to be understood that the translating device may take other forms, and the receiving coil may be replaced by any device responsive to variations in the electrical energy supplied to the receiving unit.

It is to be noted, when the usual choke coil is used in the smoothing means, that there is a loss of power therein due to the impedance of the choke coil. This loss is a complete waste. In this invention the field unit of the translating device acts also as a choke coil and produces a useful field as well. Thus a considerable part of the power ordinarily wasted in the usual choke coil is effectively utilized for the useful purpose of producing the field of the translating device.

It is apparent that the impedance of the field unit can be made any value desired. For instance, it may be made sufficiently large to wholly replace the choke coil.

The field producing means or unit of the loud speaker may be utilized for a further purpose. For example, it is sometimes desirable to have a point of fixed potential in the receiving system as, for instance, when screen grid tubes are employed. This is easily accomplished by providing a tap or intermediate point 85 in the winding of the loud speaker, so that the desired potential drop, and consequently the desired potential, may be obtained without the use of auxiliary resistances, such as 19 or 42, 44 and 46, or 67 or 71, or other apparatus. This arrangement is particularly useful, when the field unit is connected in parallel with the output or power supply circuits, as clearly shown in Figure 3 and Figure 4.

While one form or type of translating device has been given as one example of the many embodiments that the invention may take, it is to be understood that any other suitable, similar or equivalent translating device, adapted to translate electrical impulses or variations into mechanical motion or sound and having field pro-

- ducing means requiring a unilateral current or potential for its excitation, may be equally well used without departing from the spirit and scope of the invention as set forth in the appended 5 claims.
- Further, it is to be noted that while one form of current converting means has been given in the drawings as an example, it is to be understood that any other equivalent or similar current converting means may be employed without departing from the spirit and scope of this invention. 10
- It will be seen that a novel form of wireless receiving system has been provided by this invention in which the field producing means or unit of the translating device and the output circuits of one or more of the electron discharge devices are supplied from the same source through one or more electrical circuits. 15
- Further, it will be seen that in certain forms of the invention the field producing means or unit itself furnishes a portion of the impedance in the filter system or filter circuit. 20
- For the sake of definiteness it is to be noted that super-audio frequencies are defined as frequencies above the audio range. 25
- It is to be clearly understood that while the drawings and specification disclose only a few embodiments of the invention, which are given merely as examples, the invention is by no means limited to the exact form or forms or to the number of electron discharge devices or to the precise circuit connections as indicated, or to a particular system, or arrangement of circuits in radio receiving work or vacuum tube systems, but various changes or modifications both in the electron discharge devices and in the circuit connections are contemplated and are to be considered as being within the scope and spirit of the invention as developed in the claims. Therefore, although this invention has been described in considerable detail, it is to be understood that such description is intended as illustrative rather than limiting, as the invention may be variously embodied and is to be interpreted as claimed. 45
- In construing the appended claims it should be clearly understood that the expression "a number" appearing in some of said claims has its mathematical meaning, namely, an integer, in the present case, which may be either unity or a larger number. In other words, said term as used in the present case is of the same scope as "one or more". 50
- I claim:
1. In a radio receiving apparatus, the combination of alternating current supply means, detecting and amplifying means including a plurality of electron discharge devices, said discharge devices having cold and cathode electrodes and being mounted in cascade, the cathode of a number of said discharge devices being an indirectly heated cathode provided with cathode heating means, rectifying means mechanically distinct from said detecting means for supplying cold electrode potential from said current supply means, circuit connections for heating the cathodes of said discharge devices from said current supply means, an electrodynamic sound reproducer having an armature winding supplied with electrical impulses from the last electron discharge device of the cascade in said apparatus and having a field winding conductively connected to said rectifying means and energized with rectified current from said current supply means through said rectifying means substan-
- tially independently of the heating current actuating the cathodes of said discharge devices, and circuit connections conductively connecting said rectifying means to the corresponding cathode and cold electrodes of a plurality of said discharge devices substantially independently of said field winding. 80
2. In a radio receiving apparatus, the combination of an alternating current supply source, detecting and amplifying means, said detecting and amplifying means including a plurality of electron discharge devices having current-heated cathode and anode electrodes, said detecting means having indirectly heated cathode and anode electrodes, said amplifying means including an audio frequency amplifier, rectifying means mechanically distinct from the electrodes of said detecting means for supplying anode positive potential from said current supply source, an electrodynamic sound reproducer having a movable coil supplied with electrical impulses from said audio amplifier and having a field winding conductively connected to said rectifying means and supplied therefrom with rectified current and energized substantially independently of the heating current actuating the cathodes of a plurality of said discharge devices, and circuit connections conductively connecting said rectifying means to the anode and cathode electrodes of a plurality of said discharge devices 95 substantially independently of said field winding. 96
3. In a radio receiving apparatus, the combination of a plurality of thermionic devices mounted in cascade and having current-heated cathode and anode electrodes, current supply means mechanically distinct from the cathodes of said thermionic devices, impedance means connected to said current supply means and to a number of said thermionic devices for supplying suitable anode positive potential from said current supply means, and a translating device having an armature member supplied from the output of the last thermionic device of the cascade in said apparatus and having a field winding conductively connected to said current supply means, 100 and circuit connections whereby said field winding is actuated from said current supply means substantially independently of the heating current energizing the cathodes of said thermionic devices and actuated substantially independently 105 of the anode-cathode current supplied from said current supply means in said apparatus. 110
4. In a radio receiving apparatus, the combination of a plurality of thermionic devices mounted in cascade and having current-heated cathode and anode electrodes, an operating current source, rectifying means, resistance means connected to said source through said rectifying means and to a number of said thermionic devices for maintaining suitable anode-cathode 115 potentials in said apparatus, and a translating device having an armature coil supplied from the output of said apparatus and having field producing means conductively connected to said source, and circuit connections whereby said field producing means is actuated from said current source substantially independently of the heating current energizing the cathodes of said thermionic devices and actuated substantially independently 120 of the anode-cathode current supplied from said current supply means in said apparatus. 125
5. In a radio receiving system, the combination of a source of operating current, rectifying means supplied from said source, detecting 130
- means

- and amplifying means including a plurality of co-operating electron discharge devices having cathode and anode electrodes, a translating device having a field winding and having an armature member associated with the output circuit of one of said discharge devices, means conductively connecting the return of said cathodes and one side of said field winding to one point of said source independently of said cathodes, and means 5 conductively connecting through said rectifying means another point of said source to a second side of said field winding and to the anodes of a plurality of said discharge devices independently of said field winding.
- 15 6. In a radio receiving system, the combination of current supply means, current converting means supplied from said current supply means, amplifying and detecting means including a plurality of electron discharge devices having cathode and anode electrodes, a translating device adapted to be actuated with signal energy from one of said electron discharge devices and having field producing means actuated independently of the heating current activating the cathodes of said discharge devices, resistance means supplied from said current supply means through said current converting means, means conductively connecting said resistance means and the anodes of certain at least of said discharge devices to one point of said current supply means through said current converting means independently of said field producing means, and means conductively connecting said field producing means and the cathodes of said discharge 30 devices to a second point of said current supply means.
7. In a radio receiving apparatus, the combination of alternating current supply means, detecting and amplifying means including a plurality of electron discharge devices, the cathode of at least one of said discharge devices being an indirectly heated cathode, rectifying means for supplying anode positive potential to certain at least of said discharge devices from said current supply means, and an electrodynamic sound reproducer having an armature winding actuated with electrical impulses from an electron discharge device of said apparatus and having a field winding conductively connected to said rectifying means, said field winding having at least a part supplied with rectified current from said rectifying means, said rectifying means being conductively connected between the anode and cathode electrodes of one at least of said discharge devices independently of at least a part of said field winding and being conductively connected between the anode and cathode electrodes of another of said discharge devices through at least a part of said field winding.
- 55 8. In a radio receiving apparatus, the combination of a source of current, detecting and amplifying means including a plurality of electron discharge devices having cathode and anode electrodes, the cathode of a number of said discharge devices being an indirectly heated cathode, and an electrodynamic sound reproducer having a field winding conductively connected to said source and supplied therefrom, said source being conductively connected to the anode and cathode electrodes of a discharge device in said apparatus substantially independently of said field winding for maintaining a voltage between said anode and cathode electrodes and being conductively connected to the anode and 70 cathode electrodes of another of said discharge

devices through said field winding for maintaining a voltage between the anode and cathode electrodes of said last mentioned discharge device.

9. In a radio receiving apparatus, the combination of a plurality of thermionic devices, operating current supply means, a plurality of reactors substantially mechanically distinct from each other connected to said current supply means for smoothing fluctuations of the electricity supplied from said current supply means, one of said reactors forming the field winding of an electrodynamic sound reproducer, and anode circuits for said thermionic devices connected with said reactors at different points whereby one at least of said anode circuits is supplied with operating potential different from that supplied to another of said anode circuits from said current supply means.

10. In a radio receiving apparatus, the combination of an electron discharge device having a plurality of electrodes, a power source for supplying electricity to said discharge device, a plurality of inductances mechanically distinct from each other acting as a filter for the electricity supplied from said source, one of said inductances constituting the field producing means of a sound reproducing device, and a conductive connection from one of said electrodes to a point between said inductances.

11. In a radio receiving apparatus, the combination of amplifying and detecting means including a plurality of thermionic devices, a source of operating current, a plurality of filter inductances substantially mechanically distinct from each other and connected to said source for smoothing fluctuations of electricity supplied from said source, anode circuits for said thermionic devices connected to said inductances and electrically separated by one of said inductances, and a translating device having a movable coil supplied from the output of said apparatus and having a field winding forming one of said inductances and actuated substantially independently of the heating current energizing the cathodes of said thermionic devices.

12. In combination, a radio receiver including a plurality of electron discharge devices, a power source connected between the anode and cathode electrodes of said discharge devices for supplying anode potential thereto, a filter network, including a plurality of inductances mechanically distinct from each other, connected to said power source and said discharge devices, an electrodynamic sound reproducer having an armature winding supplied with electrical impulses from said radio receiver and having a field winding forming one of said inductances, means including said field winding, in which a drop of potential is produced due to the flow of current in the said winding, and means whereby said first mentioned means will supply a correspondingly decreased voltage between the anode and cathode of an electron discharge device in said apparatus in order to maintain a voltage between the said anode and said cathode of said last mentioned discharge device different from that applied substantially independently of said field winding between the anode and the cathode of another of said discharge devices.

13. In a radio receiving apparatus, the combination of a plurality of electron discharge devices provided with anode circuits, a power source, and an electrodynamic sound reproducer having field producing means supplied

- from said source and interposed wholly between two anode circuits and arranged to serve as smoothing means for reducing fluctuations of the electricity supplied from said source to at least one of said anode circuits, and, at the same time, to produce a field for said sound reproducer, said field producing means having one terminal connected to said power source and to one of said anode circuits and having a second terminal connected to another of said anode circuits whereby said field producing means is adapted also to maintain one of said anode circuits at a potential different from that supplied substantially independently of said field producing means to another of said anode circuits from said power source. 10
14. In a radio receiving system, the combination of operating current supply means, a plurality of electrical circuits having a common portion and including rectifying means and being supplied from said current supply means, said electrical circuits having a plurality of positive output terminals, one terminal being supplied from a rectifier electrode separate and distinct from that supplying another output terminal, detecting and amplifying means including a plurality of electron discharge devices having current-heated cathode and anode electrodes, said detecting means having an indirectly heated cathode mechanically distinct from any element of said rectifying means, said discharge devices being mounted in cascade in said apparatus, a translating device provided with a movable coil adapted to be actuated by the output of the last electron discharge device of the cascade in said apparatus and having field producing means actuated independently of the heating current energizing the cathodes of a plurality of said discharge devices, means connecting each of said electrical circuits to a number of discharge device anodes in said apparatus, and means electrically connecting the said field producing means to a number of said electrical circuits, whereby said electrical circuits supply anode positive potential from said current supply means, and whereby a number of said electrical circuits supplies current from said current supply means to said field producing means for energizing the same. 15
15. In a radio receiving system, the combination of variable current supply means, a plurality of electrical circuits having a common portion and including current converting means, said electrical circuits having a plurality of positive output terminals one output terminal being supplied from a current converter terminal separate and distinct from that supplying another output terminal, detecting and amplifying means including a plurality of cooperating electron discharge devices, one of said discharge devices having an indirectly heated cathode connected to an anode through an anode circuit, another of said discharge devices having a cathode connected to an anode through a part of one of said electrical circuits, the cathodes of said discharge devices being mechanically distinct from said current converting means, circuit connections for heating the cathodes of said electron discharge devices from said current supply means, a translating device for translating electrical impulses into sound and having field producing means, means connecting each of said electrical circuits to a number of discharge device anodes in said apparatus, and means connecting said field-producing means to a number of said electrical circuits, whereby said electrical circuits supply anode positive potential from said current supply means, and whereby a number of said electrical circuits supplies current from said current supply means to said field producing means for energizing the same. 20
16. In a radio receiving system, the combination of alternating current supply means, a plurality of electrical circuits having a common portion and supplied from said current supply means and including rectifying means, said electrical circuits having a plurality of positive output terminals one terminal being supplied from a rectifier electrode separate and distinct from that supplying another output terminal, amplifying and detecting means including a plurality of cooperating electron discharge devices mounted in cascade, one of said discharge devices having an indirectly heated cathode connected to an anode through an anode circuit, another of said discharge devices having a cathode connected to an anode by a part of one of said electrical circuits, circuit connections for heating the cathodes of said electron discharge devices with alternating current, a translating device adapted to be actuated from the last electron discharge device of the cascade in said apparatus and having field-producing means electrically connected to a number of said electrical circuits and supplied therefrom, and means connecting each of said electrical circuits to a number of discharge device anodes in said apparatus, whereby said field producing means aids in smoothing out pulsations in current supplied from said current supply means, and whereby said electrical circuits supply anode rectified positive potential from said current supply means in said apparatus. 25
17. In a radio receiving system, the combination of alternating current supply means, a plurality of electrical circuits having a common electrically conductive portion and including rectifying means supplied from said alternating current supply means, said electrical circuits having a plurality of positive output terminals one terminal being supplied from a rectifier electrode separate and distinct from that supplying another output terminal, smoothing means connected to a number of said electrical circuits, detecting and amplifying means including a plurality of cooperating electron discharge devices mounted in cascade and having cold electrodes, one of said discharge devices having an indirectly heated cathode connected to a cold electrode by an electrode circuit, another of said discharge devices having a cathode connected to a cold electrode through a part of one of said electrical circuits, said indirectly heated cathode being mechanically distinct from said rectifying means, a translating device for translating current variations delivered from the last electron discharge devices of the cascade in said apparatus into sound and having field producing means, means electrically connecting said field producing means to a number of said electrical circuits, whereby said last named number of electrical circuits supplies rectified potential to said field producing means from said current supply means, and means connecting the cold electrodes of a plurality of said discharge devices to a number of said electrical circuits, whereby said last mentioned cold electrodes are supplied with rectified potential from said current supply means through a number of said electrical circuits. 30
18. In a radio receiving system, the combination of a source of operating current, a plurality of electrical circuits having a common electrically conductive portion and including rectifying

means supplied from said source, said electrical circuits having a plurality of positive output terminals one terminal being supplied from an electrode of said rectifying means distinct from 5 that supplying another positive output terminal, amplifying and detecting means including a plurality of cooperating electron discharge devices having cathode and anode electrodes, a number of said discharge devices having an indirectly 10 heated cathode and an anode connected to one of said electrical circuits and having its electrodes mechanically distinct from any element of said 15 rectifying means, another of said discharge devices having an anode conductively connected to one of said electrical circuits and supplied therefrom, and a translating device having an armature coil supplied from the output of one of said 20 discharge devices and having a field winding conductively connected to one of said electrical circuits and supplied therefrom.

19. In a radio receiving system, the combination of an electron discharge device having electrodes including cathode, anode and grid, an electrodynamic loud-speaker device having an actuating coil and a field winding, means mechanically distinct from all the electrodes of said discharge device to effect a flow of current in said field winding and in said discharge device, a conductive impedance having at least a portion in 25 shunt to said field winding, and connections between at least two of the electrodes of said discharge device and points, at least one of which is intermediate between the terminals of said impedance, between which points exists the potential difference applied between said last mentioned electrodes.

20. In a radio receiving system, the combination of a plurality of electron discharge devices having thermionic cathodes and a plurality of 30 cold electrodes, an electrodynamic sound reproducer having a movable coil and a field winding, means mechanically distinct from all the electrodes of said discharge devices for effecting a flow of direct current in said field winding and 35 for supplying operating potential to a cold electrode of certain at least of said discharge devices, conductive impedance means having at least a portion in shunt to said field winding, and connections from the cold electrodes of certain at least of said discharge devices to points of said 40 impedance means at potentials suitably different in magnitude from that applied across said field winding.

21. In a radio receiving apparatus, the combination of a plurality of electron discharge devices having thermionic cathodes and a plurality of cold electrodes, an electrodynamic sound reproducer having an actuating coil and a field winding, means mechanically distinct from the 45 electrodes of said discharge devices for effecting a flow of direct current in said field winding and for supplying operating potential to a cold electrode of certain at least of said discharge devices, conductive impedance means having at 50 least a portion in shunt to said field winding, a connection from one side of said field winding to the cathodes of certain at least of said discharge devices, and connections between the cold electrodes of certain at least of said discharge devices 55 and certain points of said impedance means, whereby an operating voltage is applied between the cathode and a cold electrode of one at least of said discharge devices different from that applied between the cathode and the cold electrode 60 of another of said discharge devices.

22. In a radio receiving apparatus, the combination of an electron discharge device having a plurality of electrodes, an electrodynamic translating device having field producing means, means mechanically distinct from the electrodes of said discharge device for energizing said field producing means and said discharge device, a resistance having at least a portion in shunt to said field producing means, and a conductive connection from one of said electrodes to a point between the 65 terminals of said resistance.

23. In a radio receiving apparatus, the combination of an electron discharge device having electrodes, an electrodynamic translating device having field producing means, means mechanically distinct from the electrodes of said discharge device for energizing said field producing means and at least one of the said electrodes, and a resistance device having at least a portion in shunt to said field producing means and having a tap conductively connected to one of said electrodes.

24. In a radio receiving apparatus, the combination of a plurality of electron discharge devices having electrodes, an electrodynamic sound reproducer having field producing means, means mechanically distinct from the electrodes of said discharge devices for energizing said field producing means and certain at least of said discharge devices, resistance means having at least a portion in shunt to said field producing means, and tapped 100 appropriately to supply with electricity a plurality of said electrodes.

25. In combination, a radio receiver including a plurality of electron discharge devices having electrodes provided with circuits, an electrodynamic sound reproducer having field producing means, and conductive impedance means having at least a portion in shunt to said field producing means and being tapped appropriately to serve as a voltage divider for said circuits.

26. In a radio receiving apparatus, the combination of a source of current, amplifying and detecting means including a plurality of electron discharge devices, rectifying means mechanically distinct from the electrodes of said discharge devices 110 and supplied from said source, an electrodynamic sound reproducer having field producing means, conductive impedance means connected to said rectifying means and supplied from said source, connections between said field producing means 115 and points, one of which is intermediate the terminals of said impedance means, between which points exists a potential difference applied to said field producing means, and means between said impedance means and a number of said discharge 120 devices for energizing the same from said source.

27. In a radio receiving apparatus, the combination of amplifying and detecting means including a plurality of thermionic devices having cathode and anode electrodes, the cathode of a number of said thermionic devices being an indirectly heated cathode, a source of alternating current, rectifying means supplied from said source, impedance means connected to said rectifying means and to certain at least of said thermionic devices 135 for supplying suitable anode potential in said apparatus from said source through said rectifying means, a translating device having a movable coil supplied from the output of said apparatus and having field producing means actuated substantially independently of the heating current energizing the cathodes of said thermionic devices, and means mechanically distinct from the means designed to supply cathode heating current to said rectifying means conductively connecting said 140

- source to said field producing means through said rectifying means.
28. In a radio receiving apparatus, the combination of a source of current, detecting and amplifying means including a plurality of space discharge devices, rectifying means supplied from said source, a translating device having a movable coil actuated from the output of a space discharge device in said apparatus and having a field 5 winding, resistance means connected to said rectifying means and to certain at least of said discharge devices, means conductively connecting one side of said field winding and one side of said resistance means to one point of said source, and means conductively connecting a second side of said field winding and a second side of said resistance means to another point of said source independently of the filaments of said discharge devices, whereby said source supplies current to 10 said field winding and positive anode potential in said apparatus.
29. In a radio receiving system, the combination of variable current supply means, an electrical circuit including current converting means supplied from said current supply means, amplifying and detecting means including a plurality of cooperating electron discharge devices having cathode and anode electrodes, a number of said discharge devices having an indirectly 15 heated cathode connected to an anode by an anode circuit, a translating device adapted to be actuated from one of said discharge devices and having field producing means, said current converting means being connected to said field producing means and to the anode electrodes of certain at least of said discharge devices, and a condenser connected across the terminals of said field producing means, whereby said current supply means supplies simultaneously current to 20 said field producing means and positive anode potential in said apparatus.
30. In a radio receiving system, the combination of alternating current supply means, current converting means supplied from said current supply means, amplifying and detecting means including a plurality of cooperating electron discharge devices having cathode and anode electrodes, a number of said discharge devices having an indirectly heated cathode connected to an anode 25 by an anode circuit and having said indirectly heated cathode mechanically distinct from said current converting means, circuit connections for energizing the cathodes of said electron discharge devices with alternating current, a translating device for translating variable current into sound and having field producing means, said translating device being adapted to be actuated with signal energy from one of said discharge devices, said converting means being connected to said field 30 winding, resistance means connected to said rectifying means and to certain at least of said discharge devices, means conductively connecting one side of said field winding and one side of said resistance means to one point of said source, and means conductively connecting a second side of said field winding and a second side of said resistance means to another point of said source independently of the filaments of said discharge devices, whereby said source supplies current to said field winding and positive anode potential in said apparatus.
31. In combination, a radio receiver including an electron discharge device having a cathode and a screen grid, a power source for supplying potential to at least said grid, and an electrodynamic translating device having a field winding connected to said power source and having a tap connected to the said grid to maintain it at a suitable potential with respect to said cathode, said field winding being energized from said power source.
32. In combination, a radio receiver including an electron discharge device having a screen grid and a plurality of other electrodes, a power source for supplying voltage to at least one of said electrodes, and an electrodynamic sound reproducer having a field winding connected to said power source, said field winding having a tap connected to said screen grid for maintaining a voltage difference between said grid and a second electrode of said discharge device from said power source, said field winding acting as a filter for the electricity supplied to at least one of the electrodes of said discharge device.
33. In combination, a radio receiver including an electron discharge device having a cathode and a screen grid, a power source for supplying potential to at least said screen grid, and an electrodynamic translating device having a field winding connected to said power source and energized therefrom, and a connection between said screen grid and said field winding whereby said screen grid is supplied with potential from said power source through said field winding.
34. In combination, a radio receiver including an electron discharge device having a screen grid and a plurality of other electrodes, a power source for supplying voltage to at least one of said electrodes, and an electrodynamic sound reproducer having a field winding connected to said power source, and means conductively connecting said field winding to said screen grid for maintaining a voltage difference between said screen grid and a second electrode of said discharge device from said power source, said field winding acting as a filter for the electricity supplied to said screen grid.
